CLAIM

The ornamental design for an adjustable cargo carrier assembly, as shown and described.

DESCRIPTION

FIG. 1 is perspective view of the adjustable cargo carrier assembly of the present design;

FIG. 2 is a top view of the adjustable cargo carrier assembly of the design of FIG. 1;

FIG. 3 is a bottom side view of the adjustable cargo carrier assembly of the design of FIG. 1;

FIG. 4 is an end view of the adjustable cargo carrier assembly of the design of FIG. 1;

FIG. 5 is a side view of the adjustable cargo carrier assembly of the design of FIG. 1; and,

FIG. 6 is a perspective view of an alternate configuration of the adjustable cargo carrier assembly of the design of FIG. 1.

In the drawings, the broken lines depict environmental subject matter only and form no part of the claimed design.

1 Claim, 5 Drawing Sheets
